ABSTRACT

The present invention relates to a rug making device, and more particularly relates to a rug making device for making fluff rugs having selectable pile depth, having a sculptured texture, having fringed borders, and the like. The disclosed rug making device is such that it may be quickly and easily adjusted to produce yarn strands of selectable length for the above purposes; several embodiments of the adjustable rug making device being disclosed.

13 Claims, 5 Drawing Figures

RUG MAKER

BACKGROUND

Many homemakers have recently become very interested in the making of the so-called "fluff rugs;" partly because of the unusually pleasing appearance that this type of rug can produce, and partly because of a new device for facilitating the making such rugs.

In the past, these fluff rugs were made by hand forming a plurality of yarn strands into a bundle by tying together their central portions; and then either hand sewing or hand tying the center of the bundle to a rug backing. When a plurality of such bundles are fastened sufficiently close together, the individual strands of yarn tend to assume an erect orientation; thus producing a soft fluff rug. By using yarns of selected colors, and by arranging the yarn bundle into pleasing patterns, very attractive rugs may thus be made.

On of the disadvantages of the early fluff rug procedure described above, was the uneven alignment produced by an inexperienced person when the yarn bundles were affixed to the rug backing; but this problem was obviated by the rug making device disclosed in co-pending U.S. Patent application Ser. No. 141,223 — Rug Making Device And Method Of Use — Filed May 7, 1971 by Myrtle B. McHale. The operation of that device will become apparent from a later description to be presented in this patent application.

Due to the increased interest in fluff rugs aroused by the above disclosed rug making device, it has been found that the appearance of fluff rugs can be vastly improved by (A) selectively varying the length of the strands used, and (B) by varying the form of the resultant yarn configuration — these factors introducing a "deep pile" rug, a "sculptured" rug, additional novel rug patterns, etc.

While the above disclosed rug making device facilitates the making of fluff rugs, and permits unskilled operators to produce excellent rugs, that rug making device had the shortcoming that its use was limited to rugs having a pile depth of about one inch.

OBJECTIVES AND DRAWINGS

It is therefore the principal object of the present invention to provide an improved rug making device.

It is another objective of the present invention to provide an improved rug making device that is adapted to make rugs of selectable pile thickness.

It is a further objective of the present invention to provide an improved rug making device for making rugs having various yarn forms.

It is a further objective of the present invention to provide an improved rug making device that is readily adjustable for yarn strand length.

It is a still further objective of the present invention to provide an improved rug making device adapted to using a novel yarn hold down.

The attainment of the above objects and others will be realized from a study of the following specification taken in conjunction with the drawings of which:

FIG. 1 shows a basic adjustable rug making device;

FIG. 2 shows another embodiment of an adjustable rug making device;

FIG. 3 shows a partial cutaway view of another embodiment of the adjustable rug making device and one of the yarn forms that it can produce.

FIG. 4 shows another partial cutaway view of a somewhat different embodiment of the rug making device;

FIG. 5 shows a partial view of one of the adjustable rug making devices in the expanded state.

SYNOPSIS

Broadly speaking, the disclosed invention comprises a framework that has a pair of bars that may be adjustably spaced apart. Their spacing determines the length of the resultant yarn strands, which in turn determines the yarn form that produces the rug. The extreme ease of adjusting the disclosed framework facilitates the choice of yarn length, and thus provides a large variety of yarn patterns.

DESCRIPTION

15. Basic Rug Making Device

The present invention will be understood from FIG. 1. Here the rug maker 10 comprises a base element 11 that has a handle 12, and flares to a shoulder 13 that contains a plurality of spaced apart receptacles 15. As indicated, a pair of elongate bars 16A and 16B are fitted into selected receptacles 15 in order to obtain a desired spacing between the bars 16A and 16B; and, as will be shown later, to thus obtain a desired strand length for the resultant rug.

Rug maker 10 also comprises a cap element 20 that may contain a similar plurality of spaced apart receptacles that receive the other ends of bars 16A and 16B. In this way, the support elements 11 and 20 support the bars 16 securely at any desired bar separation.

As indicated in FIG. 1, a suitable yarn 23 is wound around the bars 16A and 16B of the rug maker 10, to produce a yarn winding 24; the wrapped yarn being snug enough to hold the resultant winding 24, but still being loose enough to avoid bowing the bars 16. If desired, bars 16 may have outwardly curving sectors 26 that act to hold the winding 24 in place on the rug making device 10.

The now-wound rug making device is placed on a rug backing (not shown); and a sewing machine stitch 27 is sewn down the center of the winding 24; to hold the center portion of winding 24 to the rug backing. Now, the outer portions of the winding 24 are cut along the outer longitudinal surfaces of the bars 16; cutting grooves 28 being provided for facilitating the yarn cutting operation. Once the yarn winding 24 has been cut, the rug making device 10 may be removed; leaving a yarn strip having its center portion firmly sewn to the rug backing.

The ends of bars 16 are preferably a fairly snug fit into the receptacles 15, in order that the bars will remain in their fixed location during the yarn wrapping, the winding sewing, and the yarn cutting operations.

Once the yarn strip has been affixed by sewing it to the rug backing, the rug making device 10 is removed; and is now rewound with another yarn winding — and the above procedure is repeated. In this way, a completed rug is formed by adjacent yarn strips. When so desired, selected yarn windings may use different colored yarn, and thus a colored rug pattern is produced.

In those cases when the desired pattern involves curves, the rug making device 10 is wound with only a short yarn winding; and successive short yarn strips are positioned at suitable angles to each other, to form a rug pattern of any desired length and curvature.

Adjustable Rug Making Device (I)

As indicated above, the increased interest in fluff rugs has led to a desire for rugs having various pile

depths and different rug patterns. The first of these two desiderata may be achieved by providing yarn strands of selectable length — which, in turn, may be achieved by providing yarn windings 24 having selectable "diameters." To achieve this result, the prior art rug maker would have to be available in sets; wherein the individual rug makers of the set have different spacings between their elongate bars.

However, rather than requiring each user to have a complete set of rug making devices of graduated spacings, the present rug making device 10 of FIG. 1 is adapted to have its bars adjustable spaced apart. This adjustable spacing is provided by inserting the ends of the bars 16 into selected receptacles 15 of the base element 11 and the cap element 20.

For reasons that will be understood from a later discussion, the end of the bars 16 (not shown in FIG. 1) is preferably formed into a substantially spherical globular configuration that is connected to the body of the bar by means of a reduced size neck portion. This bar end configuration permits the globular end of the bar to be "snapped" into or out of a suitable sized receptacle. This bar end snap-in construction (to be shown and discussed later in greater detail) has a number of advantages that will also be discussed later.

The above described spacing adjustment permits the operator to change the winding diameter, and to thus control the resultant pile depth at any location of the rug. In this way, the resultant rug may have a selectable rug pile depth over its entire area; or, alternatively, may have different pile depth at selected portions of the rug — thus providing a sculptured rug effect, a border having a different pile depth, etc.

Adjustment (I)

It has been found, for maximum operator convenience, that the cap element 20 of the rug making device 10 should have its overall length limited to about 6 inches; and preferably should be as short as possible. In order to achieve this result, cap element 20 — rather than being just as wide as shoulder 13, and having like plurality of receptacles therein — may be formed in such a way that it is longitudinally telescopic; that is, its inner portion 30 can slide into its outer portion 31, in a telescopic manner. When cap element 21 is formed in this telescopic way, its overall length may be limited to about two-thirds of the width of the shoulder; and only two end position receptacles are required. Thus, the first ends of the bars 16 may be brought closer together or farther apart by telescopically adjusting the length of the cap element 30; and the other ends of the bars may be brought closer together or farther apart by inserting them into suitably spaced receptacle 15.

In order to hold the cap element 20 at the desired telescopic position, it may be provided with any suitable "detent;" one form of such a detent comprising a plurality of spaced apart mounds or "pimples" 33 positioned along the top of the inner cap end 30 — these pimples being suitably spaced to engage "dimples" (not shown) that are complementarily spaced apart along the inner top surface of the outer cap end 31. Detents of this type are easily formed; particularly if the cap element 20 is made of plastic, metal, wood, or a similar material.

Thus, in accordance with the teachings of the present invention, the rug making device 10 may have a shoulder width of about 6 inches whereas its cap end may have an overall length of about four inches. This means

that the device can make a rug having a pile depth ranging from about one-half an inch to about 3 inches.

However, as stated previously, it is often desirable to make a rug having a much deeper pile; and achievement of this result will be understood from the rug making device shown in FIG. 2.

Adjustable Rug Making Device (II)

FIG. 2 shows a pictorial view of another adjustable spacing rug making device 35, illustrated as being in its collapsed state, for producing a shallow pile rug. As shown in FIG. 2, rug maker 35 is a frame that comprises a supporting base element 36 and a supporting cap element 37 that are interconnected by a pair of bars 38A and 38B; the bars 38 being shown in their closest position.

The above result is achieved by forming both the base 36 and the cap 37 into a telescoping configuration — each having a longitudinal inner structure (39 and 40 respectively) and a hollow longitudinal outer structure (41 and 42 respectively) — that slides longitudinally in a telescopic manner. The inner structures 39 and 40 are indicated to be somewhat longer than the outer structures 41 and 42; so that when the base 36 and the cap 37 are both completely telescoped, a portion of the inner structures 39 and 40 still protrudes out of the outer structures 41 and 42.

As indicated, corresponding walls of the inner and outer structures of the base 36 and the cap 37 are pierced with suitably spaced apart receptacles indicated in the cap 37 by reference character 44.

The spacing of the receptacles is such that at any given telescopic position, selected receptacles of the inner structure align themselves with selected receptacles of the outer structure. In the collapsed position shown in FIG. 2, the receptacle alignment permits the ends of the bar 38B to be received by an aligned pair of receptacles — thus supporting the bar 38B securely in place. Meanwhile, the exposed receptacle of the inner structures 39 and 40 of the base 36 and the cap 37 receive the ends of bar 38A; supporting it securely in place.

With the rug making device 35 in its collapsed telescope position as shown, the bars 38A and 38B are placed at their closest possible spacing; and a yarn winding 43 may be thus positioned on the rug making device 35 — the yarn winding having a "diameter" of as little as 1 inch, thus producing a rug having a very shallow pile depth.

It will be noted that, in FIG. 2, the bars 38A and 38B are indicated to be square or rectangular, and preferably to having cutting grooves 45 along at least one longitudinal surface thereof. Thus, the bars 38A and 38B are identical; and may be used interchangeably.

Rug maker 35 is indicated to have a detent mechanism illustrated as comprising a flat spring 46, having a locking pin 47, affixed to the outer structures 41 and 42 as by means of rivets; the locking pin 47 fitting into a suitably positioned locking hole (not visible in FIG. 2). Of course, other types of detent mechanisms may be used.

FIG. 2 indicates that the base 36 and the cap 37 are formed of tubular material; end closures 49 being used for improved appearance and efficiency.

While it is not essential, it has been found desirable to have a handle 50; and FIG. 2 shows such a handle to be attached to the outer structure 41 of the base ele-

ment 36. If desired, handle 50 may extend over the smaller inner structure 39; where it will provide an additional support.

Yarn Forms

FIG. 2 indicates the yarn winding 43 to have a machine stitch 51 that is not centered; but is rather fairly close to one of the bars — 38B in this illustration. The result of the non-centered stitching may be understood from the partial view of FIG. 3. This shows that if the yarn winding 43 is cut only along bar 38A, the yarn forms longer-than-normal strands 52 at bar 38A; and forms small loops around the bar 38B.

It is obvious that the combination of the long strands 52 and the small loops 53 produce a different yarn form; and a similar loop pattern may be juxtaposed to take advantage of the new yarn form. The long strands 52 may alternatively be used as the pile, as fringes, as tassels, etc.

Bar End Configuration

Whereas, in FIG. 3, bar 38A may be lifted from the cut yarn strand 52, the bar 38B must be longitudinally withdrawn from its encircling loops. To do this, the end of bar 38B (and, if desired, bar 38A) is snapped out of the aligned receptacles of the longitudinal structure 42, (and, if desired, 39, 40 and 41). As illustrated in FIG. 3, the bars 38 may have globular heads that hold the bars in place; and may have a square or rectangular necks that locks the bars in the receptacles 44. Thus, bar 38B may be freed; and then withdrawn from its encircling loops.

Whereas FIG. 3 has shown the bars 38 and receptacles 44 to be of a locking configuration, there may be times when such a relationship is not desired; and FIG. 4 indicates a non-locking arrangement. Here, the receptacles 52 are indicated to be round; and the bars are indicated to have cylindrical necks.

The advantage of this non-locking arrangement is as follows. When the bar 53B is to be free from the outer structure of the cap element 54, its ends is unsnapped; and the entire cap element 54 is then "swiveled" around the other bar 53A as indicated — until the cap element has been rotated out of the way so that bar 53B may be withdrawn from its encircling loops. Thus, the snap/swivel arrangement provides a somewhat different way of freeing the bars from the yarn strip.

It should also be noted that, in FIG. 4, the inner structure is illustrated as being completely telescoped into the outer structure.

Adjustment (II)

As stated previously, the disclosed rug maker is adjustable to produce yarn strands of any desired length; and the manner in which this is accomplished will be understood from FIG. 5, which shows a pictorial partial view of the rug maker expanded, or untelescoped, to its maximum size. Here, the cap 37 (and the base, not shown) have both been untelescoped to their greatest extent; suitable rolled lips of the base element and the cap element preventing complete separation, if this is desired. The detent spring 46 is shown to be in its engaged position, and a plurality of locking holes 56 are now visible.

In FIG. 5, the bars 38A and 38B are shown to have their maximum spacing — which may be 8 or 9 inches or more; the bar ends being received in the most distant of the receptacles 44, and being held in the receptacles by the previously described snap-in construction. Since the bars 38 are in their most remote positions, they per-

mit the operator to form the largest possible yard winding 57 which would thus produce the longest possible strand length.

FIG. 5 indicates that the inner and outer structures 5 of the cap element 37 may be formed of a channel configurated material, suitable end closures being used as shown previously.

Sewing Aid

FIG. 5 indicates the formation of a machine stitch 58; 10 this being produced by a machine needle 59 and a sewing foot 60; the winding 57 moving in the relative direction indicated by arrow 61. In order to facilitate the sewing operation, a sewing aid 62 is used — being held down by the operator's finger, so that the tip of the sewing aid 62 depresses the individual strands of the winding 57 just as these strands enter the sewing foot 60 to be sewn to the rug backing. In this way, an improved machine stitch is produced.

I claim:

1. The combination comprising: a pair of bars adapted to be adjustably spaced apart; a first support element having at least two spaced apart receptacles and comprising inner and outer telescopic structures;

means for telescoping said inner structure into said outer structure for adjusting the spacing between said receptacles;

and a second support element having at least two spaced apart receptacles;

each of said receptacles being adapted to receive an end of a said bar;

the ends of said bars being positioned in said receptacles to space said bars apart by a selected distance.

2. The combination of claim 1 including detent means for holding said first support element in a selected telescopic position.

3. The combination of claim 1 wherein said second support element has a plurality of spaced apart receptacles for receiving the ends of said bars in accordance with the positions of said bars as established by said telescopic position of said first element.

4. The combination comprising: a pair of bars adapted to be adjustably spaced apart; and first and second telescopic support elements

each having at least two spaced apart receptacles to have a given spacing by telescopic adjustment; each of said receptacles being adapted to receive an end of one of said bars;

the ends of said bars being positioned in said receptacles to space said bars apart by a selected distance.

5. The combination of claim 4 wherein both said support elements comprise hollow longitudinal outer structure having a plurality of spaced apart receptacles piercing one wall of said outer structure, and longitudinal inner structure having a plurality of spaced apart receptacles piercing a corresponding wall of said inner structure;

said inner structure being adapted to slide in a telescope manner in said outer structure;

said receptacles of said structures being suitably spaced apart to become aligned with respective other said receptacles when said inner and outer structures are telescoped.

6. The combination of claim 5 including closure means for closing the ends of said longitudinal structures.

7. The combination of claim 5 wherein both said inner and outer structures are substantially the same length.

8. The combination of claim 5 wherein said inner structure is somewhat longer than said outer structure. 5

9. A rug maker comprising:

a pair of bars, having snap-in ends, adapted to be adjustably spaced part;

a telescopic cap element having an hollow longitudinal outer structure having a plurality of spaced apart receptacles piercing one wall of said outer structure, and having a longitudinal inner structure having a plurality of spaced apart receptacles piercing a corresponding wall of said inner structure; 15

said inner structure being adapted to slide in a telescope manner within said outer structure;

a telescopic base element having a hollow longitudinal outer structure having a plurality of spaced apart receptacles piercing one wall of said outer structure, and having a longitudinal structure having a plurality of spaced apart receptacles piercing 20

10

a corresponding wall of said inner structure; each of said receptacles being adapted to receive an end of a bar;

said receptacles of said structures being suitably spaced apart to become aligned with other said receptacles when said inner and said outer structures are telescoped to a given extent;

detent means for holding said cap element and said base element in selected telescopic positions; the ends of said bars being positioned in selected said receptacles of said base and cap elements to space said bars apart by a selected distance.

10. The combination of claim 9 wherein said bars have a cutting groove along one longitudinal surface thereof.

11. The combination of claim 10 including a handle attached to said base element.

12. The combination of claim 11 wherein the ends of said bars have a snap/swivel configuration.

13. The combination of claim 11 wherein the ends of said bars have a snap/lock configuration.
